CLAIM

The ornamental design for a carpenter's layout marker holder, as shown and described.

DESCRIPTION

FIG. 1 is an isometric view of a carpenter's layout marker holder showing my new design.

FIG. 2 is a front view thereof.

FIG. 3 is a top view thereof.

FIG. 4 is a right side view thereof.

FIG. 5 is a left side view thereof.

FIG. 6 is a bottom view thereof; and,

FIG. 7 is a rear view thereof.

The broken lines showing environment in the drawings are for information purposes only and form no part of the claimed design.
